Fig. 1

Fig. 2.

Fig. 3.

Fig. 4.

A technical drawing of a mechanical device, likely a lock or fastener. It features a central vertical shaft with a circular component at the top. Various parts are labeled with numbers: 31, 38, 39, 46, 44, 43, 27, 32, and 45. The word "INVENTOR" is printed below the device, followed by the name "JACK BRESLAV.".

GRAPPLE

Jack Breslav, New Haven, Conn.

Application September 11, 1950, Serial No. 184,228

4 Claims. (Cl. 294—67)

1

This invention relates to grapples and more particularly to grapples especially designed for use to engage and lift a pile of sheet stock at one location and transfer it to another location.

Relatively long sheet metal stock is usually disposed in piles upon crosswise supporting members by which the pile of stock is raised from the floor. A plurality of such supporting members are used and are spaced apart lengthwise of the sheets to properly support them in a substantially horizontal and flat position. The supporting members often project beyond the sides of the sheets and for different lengths of sheets are usually spaced apart different amounts. It is therefore desirable that the grapple be provided with sheet gripping, or engaging, members adapted to be variably spaced along the pile of sheets to avoid interference with the spaced sheet supporting members and it is one object of this invention to provide such sheet gripping, or engaging, members in a sheet lifting grapple.

It is also desirable that the horizontal and flat position in which the sheets are disposed in piles upon their supporting members be maintained while being lifted from their supports and transferred to another location and it is, therefore, another object of this invention to provide means in a grapple of the above nature for readily accomplishing this result.

Occasionally the means provided for maintaining the sheets in a flat position is not required and therefore, as another object of this invention, such means is arranged to be made temporarily inoperative.

A further object of this invention is to provide an improved form of grapple which will be relatively simple in construction, inexpensive to manufacture, readily manipulated, compact, and very efficient and durable in use.

With these and other objects in view, which will appear as the description proceeds, there has been illustrated in the accompanying drawings a preferred form in which the features and principles of this invention may be practically and conveniently embodied.

In the drawings:

Figure 1 is a top plan view of a grapple embodying the features and principles of this invention;

Figure 2 is a side view of the same;

Figure 3 is a cross-sectional view taken on the line 3—3 of Figure 2;

Figure 4 is a detail view of a sheet engaging member for the grapple; and

2

Figure 5 is a detail view of another sheet engaging member for the grapple.

Referring now to the drawings wherein like reference numerals designate like parts throughout the several views, the reference numerals 11, 12 and 13, 14 denote pairs of cross-bars, spaced apart lengthwise of the grapple and suitably supported between cross-beams 15 disposed beneath lengthwise extending parallel frame beams 16 and 17 to slide crosswise in respect to the frame. The opposing faces 18 of each pair of cross-bars have rack teeth formed thereon and arranged to mesh with a pinion 19 operatively connected to a bevel gear 20. The bevel gears 20 are operatively connected to a shaft 21 by bevel gears 22 and the shaft 21 may be rotated by a hand wheel, or pulley, 23, or by a power driven belt, not shown, engaging the pulley 23. The pulley 23 is operatively connected to the shaft 21 by means of meshing gears 24 and 25. A suitably located loop 26 is provided whereby the grapple may be attached to an overhead crane, or the like, not shown. The above referred elements of the grapple are more fully shown and described in a patent, Number 1,807,124, issued May 26, 1931, to Frederick H. Meyer.

A drop leg 27 is attached, as by welding, to the outer end of each cross-bar 11, 12, 13 and 14. The drop legs 27 attached to the cross-bars 12 and 13 are connected together by an upper lengthwise beam 28 and a lower lengthwise beam 29. The cross-bars 11 and 14 are connected together by an upper lengthwise beam 31 and a lower lengthwise beam 32. The beams 28, 29 and 31, 32 extend beyond the drop legs at each end of the grapple and the ends of the beams constituting each pair are connected together by a plate 33. A rod 34, circular in cross-section, extends from one end plate 33 to the other, through the drop legs 27, under the beam 28 and closely adjacent to it, and a rod 35, circular in cross-section, extends from one end plate 33 to the other through the drop legs 27, under the beam 31 and closely adjacent to it. A center support 36 is provided for the rods 34 and 35 and depends from each beam 28 and 31.

A plurality of sheets 30 engaging and supporting L-shaped hooks 37 are provided and are swingably supported upon each of the rods 34 and 35. Each hook 37 is provided with a lug 38 which extends outwardly from its shank 39. Each lug 38 has a hole 41 therethrough and the rods 34 and 35 pass through the holes 41 whereby the hooks 37 may swing about the rods, see dotted lines in Figure 3, and be slid lengthwise

therealong to dispose them in the desired position thereon to avoid interference with sheet supports 42, dotted lined in Figure 2. When in sheet engaging position the shanks 39 of the hooks 37 rest against, and are supported by, the beams 29 and 32.

One, or more, hooks 43, see Figures 4 and 5, are provided which are shorter than the others, 37, to position their sheet engaging surfaces 44 above the sheet engaging surfaces 45 of the hooks 37 for use in maintaining the sheets supported thereby in substantially horizontal and flat position, as they are being moved by the grapple. These hooks 43 may be slid along the supporting rods 34 and 35 to be positioned to offset the tendency of the sheets 30 to sag, either in the middle, or at the ends in accordance with the features and principles disclosed in my Patent Number 2,281,348, issued April 23, 1942. If desired, the shank 46 of the hook 43 may be a chain, see Figure 5, or other flexible member, attached to a ring 47, slideable on the rods, whereby the hook 43 may be swung out of the way when not in use.

By the provision in a grapple of the above, or like nature, of sheet engaging hooks adapted to be moved lengthwise of the grapple frame to position them in position in respect to sheet floor supporting members to avoid interference therewith is a decided advantage. The desired number of hooks may be used, more for thin, and flexible, or long, sheets and less for relatively stiff, or short, sheets thus providing efficient support for the same as they are lifted and moved to new locations. The provision of shorter hooks, for use when desired, insures that the sheets may be maintained horizontal and flat and will not slide from the grapple during transportation.

While there has been shown and described herein a preferred form of the invention, it will be understood that the novel features and principles of this invention may be embodied in other specific forms without departing from the spirit and essential attributes thereof, and it is therefore desired that the present embodiment be considered in all respects as illustrative, and not restrictive, reference being had to the claims rather than to the foregoing description to indicate the scope of the invention.

Having thus fully disclosed the invention, what is claimed as new and for which it is desired to obtain Letters Patent, is:

1. A sheet engaging and lifting grapple comprising a frame, cross-members carried by said frame, means connected to said frame to move said cross-members transversely in respect to the length of said frame, a drop leg depending from an end of each cross-member at each side of said frame, a side frame at each side of the first frame and rigidly connected to the adjacent legs, a pair of elongated elements, one extending longitudinally of each side frame and supported from the adjacent legs, and sheet engaging and supporting hooks carried by and spaced apart length-

wise along said elements and depending therefrom, said hooks being slideable along said elements.

2. A sheet engaging and lifting grapple comprising a frame, cross-members carried by said frame, means connected to said frame to move said cross-members transversely in respect to the length of said frame, a drop leg depending from an end of each cross-member at each side of said frame, a beam extending lengthwise of said frame and connected to the legs on each side of the frame, another beam extending lengthwise of said frame and connected to the lower ends of the legs on each side of the frame, a rod connected to and supported by each of said beams and extending lengthwise of said frame, and sheet engaging and supporting hooks carried by and spaced apart along and depending from each rod, each hook being slideable along the rod, said hooks being rotatably mounted on said rods and depending inside of said last mentioned beam to be supported thereby against outward swinging movement.

3. A sheet engaging and lifting grapple comprising an elongated frame, cross-members carried by said frame, means connected to said frame to move said cross-members transversely of the frame, a drop leg depending from one end of each cross-member at each side of said frame, a side frame at each side of the first frame and rigidly connected to the adjacent legs, a pair of elongated elements one extending longitudinally of each side frame and supported from the adjacent legs, and sheet engaging and supporting hooks carried by and spaced apart lengthwise along said elements and depending therefrom, said hooks being slideable along said elements, said hooks being located between said side frames to be supported thereby against outward swinging movement.

4. A sheet engaging and lifting grapple comprising an elongated frame, cross bars carried by said frame, means connected to said frame to move said cross bars transversely of said frame, a plurality of sheet engaging and supporting members at each side of said frame supported from said cross bars and movable therewith, said members being movable longitudinally of said frame, and means at each side of said frame and supported from said cross bars limiting outward displacement of said members when said members are in operative position.
